ICED TEA MAKING MACHINE OR THE LIKE

Darwin B. Maxson, Downey, Joseph F. Scheffer, La
Puente, and Julian P. Vochelli, Compton, Calif., as-
signors to Columware, Inc., Lynwood, Calif., a corpo-
ration of California

Filed Oct. 29, 1959, Ser. No. 58,118

Term of patent 14 years

(Cl. D44—26)

FIG. 1

FIG. 2

FIG. 3

FIG. 4

FIG. 5

FIG. 6

Figure 1 is an oblique isometric view of an iced tea making machine or the like, showing our new design.

Figure 2 is a front elevational view thereof.

Figure 3 is a bottom plan view thereof.

Figure 4 is a front elevational view thereof.

Figure 5 is a right side elevational view thereof.

Figure 6 is a top plan view thereof.

The dominant features of our new design are shown in solid lines.

We claim:

The ornamental design for an iced tea making machine or the like, substantially as shown and described.
